CLAIM

The ornamental design for a combined wheel chock and flag, substantially as shown and described.

DESCRIPTION

FIG. 1 is a perspective view of a combined wheel chock and flag showing my new design;

FIG. 2 is a front elevational view thereof;

FIG. 3 is a top plan view thereof;

FIG. 4 is a left side elevational view thereof; and

FIG. 5 is a right side elevational view thereof.
The broken lines in the drawing are for illustrative purposes only.
